UNITED STATES PATENT OFFICE

JOHN A. HEBB, OF HOPWOOD, PENNSYLVANIA

COIN CONTROL MECHANISM FOR VENDING MACHINES OR THE LIKE

Application filed January 27, 1930. Serial No. 423,626.

This invention relates to improvements in coin control means for vending machines or the like, and is particularly directed to control means of the character adapted to be operated by a predetermined number of coins.

A further object of my invention is to provide change-making means associated with the coin control for returning the correct change to a purchaser upon the insertion of 10 a coin greater than the denomination to be expended.

While I have shown and described my invention in connection with a newspaper vending machine, it will be understood that the 15 invention is not to be limited thereto, but may also be applied to other forms of vending machines or the like.

Additional objects and advantages will become apparent from the following specification taken in connection with the accompanying drawings, wherein:

Fig. 1 is a top plan view of a newspaper vending machine with the cover removed, showing my coin control applied thereto, and 25 in interfering position;

Fig. 2 is a longitudinal section on the line II—II of Fig. 1;

Fig. 3 is a view similar to Fig. 2, showing the projecting or discharging mechanism of 30 the vending machine advanced;

Fig. 4 is a sectional view taken on the line IV—IV of Fig. 1, showing the coin control mechanism in normal position;

Fig. 5 is a view similar to Fig. 4, showing 35 the coin control mechanism released by means of three pennies;

Fig. 6 is a sectional view on the line VI—VI of Fig. 1, showing the operation of the coin control mechanism by means of a nickel;

Fig. 7 is a view similar to Fig. 6, showing the operation of the coin control mechanism by means of a dime;

Fig. 8 is a detail section taken on the line 40 VIII—VIII of Fig. 6;

Figs. 9 and 10 are sectional views taken on the lines IX—IX and X—X of Fig. 1 respectively, and illustrate the coin changing means associated with the coin control;

Fig. 11 is a perspective view of the coin

control mechanism detached and in normal position;

Fig. 12 is a perspective view of the nickel slide of the coin control shown above its coin trough and receptacle; and

Fig. 13 is a perspective view of the exterior of the machine, particularly showing a cover plate for closing certain of the coin slots.

The vending machine shown in the drawings is generally similar to that disclosed in my pending application Serial No. 405,877, filed November 9, 1929, and comprises a main body A of box-like shape, generally rectangular in form, made of wood, metal, or other suitable material for complete protective enclosure of the interior. Casing A is provided at its lower front portion with a rectangular cavity 4 in which is mounted an inclined floor 5, resting upon a plurality of light resilient springs 6, whereby the inclined bottom 5 is capable of a considerable degree of vertical movement.

The floor or platform 5 is adapted to receive a plurality of folded newspapers 8 as shown in Fig. 2, said platform being depressed by the weight of the newspapers with sufficient slight upward pressure to maintain the uppermost unit in operative relation to the discharging fingers or arms 9.

Such fingers, as shown, project forwardly from the lower side of a main cross head 10, to which the fingers are pivoted, as by hinge connections 11. The cross head 10 is cut away as at a to permit upward movement of the fingers for the purpose of lifting the uppermost unit from the pack, and shifting it freely outward, as in Fig. 3.

Fingers 9 are provided with downwardly and forwardly projecting incision pins 12, the sharpened points of which extend into the paper of the unit sufficiently far to engage its several leaves for outward propulsion of the entire series of leaves forming the unit, when the fingers are advanced.

The upward movement of the fingers is effected by means of guide rods 14, superimposed on the fingers and pivotally connected to the stationary frame 10a as at 15. Such rods are mounted in apertured guides 16 midway of the fingers, and have their end por-

tions resting in the bifurcated ends 17 of the fingers. The configuration of the rods 14 is such as to extend over the forward edge of the cross head 10, and then downwardly and 5 forwardly in the manner described.

Said cross head is provided at its ends with forwardly extending slides 18, movable in longitudinal trackways 19 in the stationary frame 10a. Upon moving the cross head 10 10 forward, the upper surface thereof will engage the rods 14, and lift said rods and their fingers, to deliver a unit as in Fig. 3. Tension springs 20, secured to the slides 18 and the stationary frame 10a will effect a return 15 of the cross head and its fingers after completion of the delivery.

The box-like body A and the cover B are provided with co-extensive delivery shelf portions 21 and 22 respectively, forming a 20 forwardly extending shelf inclined at the general slope of the platform 5. A weather shield 23 hinged at 24 to the cover B, is adapted to normally close the delivery opening 25, and is provided with rearwardly extending ears 26 at the sides of said cover B, having arcuate slots 27 therein for limited outward movement of the shield on studs or pins 28 of the cover.

A protecting door 29 is hinged across the 30 forward end of stationary frame 10a, as at 30, and normally rests against the upper face of the shelf portion 21 in an inclined position, as in Fig. 2. Said door may be provided with an apertured guide 29a for receiving a 35 retaining rod 30a, pivoted at 31a to the frame 10a, and extending through a guide 16a on the crosshead 10, thereby securing the door 29 against wrongful entrance to the interior of the machine.

40 The weather shield 23 and the door 29 are sufficiently light to be elevated, as in Fig. 3, by the advancing unit and discharging fingers 9, and to close downwardly by gravity after retraction of the discharging fingers.

45 The forward propulsion of the cross-head 10 and its flexibly connected shifting fingers 9 is effected by means of a forwardly and backwardly movable shifting head or block 31.

50 Such block is mounted for longitudinal movement on a rear shelf 32 and is provided with a laterally extending portion 33 at one side thereof. An apertured lug 34 is secured to the portion 33 for mounting one end of 55 operating link 35. The other end of said link is connected to the upper end of lever member 36, rotatable with cross shaft 37. Such shaft extends outside of the box A at one side thereof and is provided with an operating handle lever 38, preferably integral therewith.

The forward end 39 of shifting block 31 is adapted to engage the rear edge of the cross-head 10, and to project the same forwardly 60 to the desired extent, to effect the discharge

of a paper unit. Upon rotation of the handle 38 in a forward direction, the said motion is effected by means of shaft 37, lever 36 and operating link 35.

70 For the purpose of controlling the operation of the machine, I have provided an interference mechanism so designed and arranged as to prevent operation until released by the deposit of a predetermined number of coins. While I have shown such mechanism operable for the vending of a newspaper selling at a price of three cents, it will be understood that the same may be altered by changing the number and dimensions of the parts to permit the vending 75 of units at different prices.

According, I provide a transverse stop member or bar 40, slidably mounted in suitable brackets 41, and when in interfering position, adapted to project into the path of a 80 vertical abutment 42 of the block or head 31.

85 For the purpose of actuating said member 40, a bell crank 43 is provided, pivoted at 44 and having a bifurcated arm thereof engaging a pin 45 on the member 40. The other end of the bell crank is pivotally connected by means of an intermediate link 46 to an end of a rod 47, said rod being provided with, and for the purpose of operating, a coin slide 48.

90 The coin slide 48 is slidable on a floor 48a, and is formed with a vertically depending coin receptacle 49 to receive the predetermined number of coins *c* for operation of the machine. When the mechanism is in its normal position, the bottom opening of said receptacle is closed by means of a transverse member 50.

95 A coin control plate 51 is superimposed upon the coin slide 48 and has an elongated slot 52 in the contacting face thereof to receive a projecting pin or stud 53 of the coin slide. Plate 51 is further provided with a vertical coin slot 54 therethrough, normally positioned in register with the coin receptacle 49. It will be seen that the insertion of the required number of coins *c*, i. e., three pennies in the case selected for illustration, superimposed in edge-to-edge relationship, 100 will permit the uppermost penny to project above the coin slide 48 for the purpose of forming a connecting means between the slide and the coin control plate 51. Hence, a movement of the plate 51 will then produce a movement of the slide 48, thereby withdrawing the stop member 40 from the path of the abutment 42 of the head 31, by means of the connecting linkage.

105 Obviously, the insertion of one or two pennies will provide no connection between the plate 51 and the slide 48, and the member 40 will not be withdrawn by a movement of the plate 51. The slot and pin connection 52-53 permits the plate to be moved without affecting the slide 48.

For the purpose of imparting the movement just described to the control plate 51 and by a movement of the head 31, an oscillating bell crank 55 is provided, pivoted at 56, having a roller 57 rotatable in a bifurcated end thereof, and adapted to engage a cam face 58 in said head.

The other end of the bell crank is connected at 59 to a link 60, pivotally secured 10 at 61 to a vertically extending portion 62 of the coin control plate 51. Thus, a movement of the head 31 will impart movement to the plate 51 in a direction opposite to that of the head. Tension springs 63 maintain 15 the plate 51 in its normal position and urge the roller 57 against its cam surface at all times.

Upon the insertion of the three pennies required, as hereinbefore set out, the parts 20 of the mechanism will be moved to the position shown in Fig. 5, during which movement the open-ended receptacle 49 moves over the transverse member 50, thereby permitting the two lowermost pennies to fall into 25 a suitable depository in the box A. As the head 31 reaches the end of its delivery stroke, the portion 64 of the cam surface 58 then in contact with the roller 57, recedes a slight amount to permit of a relative movement of 30 the coin control plate 51 with respect to the coin slide 48, thereby releasing the uppermost penny to fall into said depository.

When the delivery stroke of the head 31 is completed, said head and its associated 35 delivery mechanism are returned to their normal positions by means of the tension springs 20. During this return motion, the control plate 51 returns the coin slide 48 to its normal position by means of the slot and 40 pin connection 52—53, thereby returning the member 40 to interfering position, the plate 51 being assisted by the tension springs 63.

It is desirable to provide means whereby 45 the control mechanism just described may be operated by the insertion of coins greater than the denomination to be expended for the article purchased. To this end, I have shown additional coin slides 65 and 66, said slides being disposed in the same plane as the slide 48 and adapted to be operated by means 50 of a nickel and dime respectively.

The nickel slide 65 is formed with a coin slot 67 therethrough and is so positioned on the floor 48a as to contact with the slide 48. 55 Coin control plate 51 is provided with a slot 68 therethrough normally in register with the slot 67 for the introduction of a nickel n by means of a suitable guide from the outside of the vending machine. A semi-cylindrical trough 69 having a radius substantially equal to that of a nickel, is formed in the floor 48a and has a slot 70 at one end thereof immediately below said coin slots 67 and 68. The width of the slot 70 is less than the diameter of a nickel but is large enough to

permit the passage of a dime or penny. An abutment 71 extends downwardly into the trough 69 from beneath the slide 65 adjacent the slots 67 and 70.

When a nickel n is inserted in the said slots it will rest in the trough 69, and a portion thereof will extend into the slot 68 of the plate 51, thereby providing connecting means with the coin slide 65. And since the slide 65 contacts with the slide 48, movement of the plate 51 will move plate 65, which in turn moves the plate 48, to withdraw the stop member 40 as described. The nickel n will be carried to the end of the trough 69 by the abutment 71 and discharged through an enlarged opening 72 into a suitable depository.

Similarly, the dime slide 66 is formed with a coin slot 67a, and the plate 51 with a registering coin slot 68a. Said slide contacts with the slide 65, so that upon the insertion of a dime d in said coin slots, it will rest upon the floor 48a, extending upwardly into the slot 68a to provide connecting means between the slide and plate, and a movement of the plate 51 will be transmitted to the slide 66, slide 65 and slide 48, thereby withdrawing the stop member 40. The dime d is discharged into an opening 73 in the floor 48a.

The coin slides 65 and 66 extend laterally as shown for the attachment of coin changing means, including depending portions 65a and 66a respectively. To the depending portion 65a is secured a change plate 74, extending in the direction of motion of the slides, and below the open end of a penny reservoir or tube 75. The change plate 74 is slightly thinner than the thickness of two pennies, and has an opening therethrough of substantially the same diameter as a penny, normally positioned below said reservoir, as shown in Fig. 9. When the machine is operated by the insertion of the nickel n, the plate 74 will move with the slide 65, and deliver two cents change to an outer receptacle 76, where it may be removed by the purchaser.

Depending portion 66a of the slide 66 is similarly provided with a change plate 77, having a thickness slightly less than that of a nickel, and extending beneath a nickel reservoir 78. An opening therethrough is adapted to shear off a nickel from the pile in the reservoir and deliver it, with the two cents from change plate 74 to the receptacle 76 when the machine is operated by means of a dime.

It will be understood that my invention may be adapted to the vending of newspapers selling at various prices. For example, should it be desired to adapt the machine just described to the vending of a Sunday newspaper selling at a price of three cents, the dime slot only may be made available to the purchaser.

The cover B of the machine is formed with

penny, nickel and dime slots P, N and D respectively, said slots normally registering with the corresponding slots in the coin control plate 51. A cover plate 83 is provided which may be used to cover the slots N and P when vending a paper selling at the price of ten cents, or may be so placed as to cover the slot P only, when it is desired to vend a five-cent paper. In the case of vending the ten-cent paper, the change will be removed from the reservoirs 75 and 78. But when vending a five-cent paper, the pennies only will be removed from the change reservoir 75, and nickels retained in the nickel reservoir 78 to permit the return of a nickel change when a dime is inserted for the purchase of a five-cent paper.

The cover plate 83 may be secured against removal in any suitable manner, as by studs 84 extending through the cover B and secured thereto by nuts or cotter pins.

Suitable means may be provided, as the ratchets 79 and 80, and their respective pawls 81 and 82, to prevent repeated delivery strokes of the head 31 for a single release by means of the coin control. Such construction is more clearly described in my pending application supra.

30 Various changes and modifications are contemplated within the scope of the following claims.

What I claim is:

35 1. In a coin control mechanism of the character described, the combination with commodity shifting means adapted to be actuated by the operator, of an interfering member therefor, a coin control plate movable by the shifting means, a coin slide operatively connected with the interfering member for receiving a predetermined number of coins, one of said coins being adapted to engage the coin control plate to impart a movement to the coin slide for retraction of the interfering member, by a movement of the shifting means, and means for returning the plate and slide to their normal positions by a return movement of the shifting means, whereby the interfering member is returned to interfering position.

50 2. In a coin control mechanism of the character described, the combination with commodity shifting means adapted to be actuated by the operator of an interfering member therefor, a coin control plate movable by
55 the shifting means, a coin slide operatively connected with the interfering member for receiving a predetermined number of coins of a denomination less than the sum to be expended, a second coin slide positioned adjacent said first slide for receiving a coin of a denomination greater than the sum to be expended, said coin being adapted to engage
60 the coin control plate to impart a movement
65 to both of said slides for retraction of the

interfering member by a movement of the shifting means.

3. In a coin control mechanism of the character described, the combination with commodity shifting means adapted to be actuated by the operator, of an interfering member therefor, a coin control plate movable by the shifting means, a coin slide operatively connected with the interfering member for receiving a predetermined number of coins of a denomination less than the sum to be expended, a second coin slide positioned adjacent said first slide for receiving a coin of a denomination greater than the sum to be expended, said coin being adapted to engage the coin control plate to impart a movement to both of said slides for retraction of the interfering member by a movement of the shifting means, and means associated with the second slide for delivering coins in change. 70 75 80 85

4. In a coin control mechanism of the character described, the combination with commodity shifting means adapted to be actuated by the operator, of an interfering member therefor, a coin control plate movable by the shifting means, a coin slide operatively connected with the interfering member for receiving a predetermined number of coins of a denomination less than the sum to be expended, a plurality of coin slides positioned adjacent each other and said first slide for receiving coins of a denomination greater than the sum to be expended, and a coin of a denomination greater than the sum to be expended adapted to be entered into one of said plurality of slides and engage the coin control plate, to impart a movement to said slide and the first slide, for retraction of the interfering member by a movement of the shifting means, and associated means for delivering coins in change.

5. In a coin control mechanism of the character described, the combination with commodity shifting means adapted to be actuated by the operator of an interfering member therefor, a coin slide operatively connected with the interfering member, a coin receptacle therein for receiving a predetermined number of coins, a coin control plate 110 slidable on the coin slide and movable by the shifting means, a coin slot therethrough normally registering with said coin receptacle, one of said coins being adapted to extend 115 from the receptacle into said slot to impart a movement to the coin slide for retraction of the interfering member by a movement of 120 the shifting means.

6. In a coin control mechanism of the character described, the combination with commodity shifting means adapted to be actuated by the operator, of an interfering member therefor, a plurality of coin slides disposed in the same plane, one of said slides being operatively connected with the inter- 120
125

fering member, a coin control plate slidable on said slides and movable by the shifting means, registering coin slots in said plate and slides, a coin adapted to be entered into one of the slides and engage the coin control plate to impart a movement to the slide for retraction of the interfering member by a movement of the shifting means.

7. Coin control mechanism for a newspaper vending machine having delivering means and an interfering member therefor consisting of a coin control plate movable by the delivering means, a coin slide operatively connected with the interfering member for receiving a predetermined number of coins of a denomination less than the sum to be expended, a second coin slide positioned adjacent said first slide for receiving a coin of a denomination greater than the sum to be expended, said coin being adapted to engage the coin control plate to impart a movement to both of said slides for retraction of the interfering member by a movement of the delivering means, and associated means for delivering coins in change.

8. Coin control mechanism for a newspaper vending machine having delivering means and an interfering member therefor consisting of a coin control plate movable by the delivering means, a coin slide operatively connected with the interfering member for receiving a predetermined number of coins of a denomination less than the sum to be expended, a second coin slide positioned adjacent said first slide for receiving a coin of a denomination greater than the sum to be expended, said coin being adapted to engage the coin control plate to impart a movement to both of said slides for retraction of the interfering member by a movement of the delivering means, and means associated with the second slide for delivering coins in change.

9. In a coin-controlled mechanism of the character described, the combination with commodity shifting means adapted to be actuated by the operator, of an interfering member therefor, a coin-controlled plate movable by the shifting means, a coin slide operatively connected with the interfering member, and registering coin-receiving slots in the said plate and slide adapted to be connected by a coin to impart a movement to the coin slide for retraction of the interfering member by a movement of the shifting means.

10. In a coin-controlled mechanism of the character described, the combination with commodity shifting means adapted to be actuated by the operator, of an interfering member therefor, a coin-controlled plate movable by the shifting means, a plurality of coin slides operatively connected with the interfering member, a plurality of coin-receiving slots in the coin controlled plate, and coin-receiving slots in the coin slides reg-

istering with slots in the control plate, any of said registering slots being adapted to be connected by a coin to impart a movement to the coin slide for retraction of the interfering member by a movement of the shifting means.

In testimony whereof I hereunto affix my signature.

JOHN A. HEBB.
